UNITED STATES PATENT OFFICE.

OSCAR E. PLEMON, OF PORTLAND, OREGON, ASSIGNOR OF ONE-HALF TO L. P. HORRESCHOW,
OF PORTLAND, OREGON.

PLATE-LIFTER.

No. 893,541.

Specification of Letters Patent.

Patented July 14, 1908.

Application filed August 26, 1907. Serial No. 390,227.

To all whom it may concern:

Be it known that I, OSCAR E. PLEMON, a citizen of the United States, residing at Portland, in the county of Multnomah, State of Oregon, have invented certain new and useful Improvements in Plate-Lifters; and I do hereby declare the following to be a full, clear, and exact description of the invention, such as will enable others skilled in the art to which it appertains to make and use the same.

This invention relates to new and useful improvements in plate lifters, and more particularly to a device of this class embodying coöperating spring arms and including an element for adjusting these arms laterally with respect to one another.

The object of the invention is to provide a novel construction, combination and arrangement of parts, the details of which will appear in the course of the following description, in which reference is had to the accompanying drawings forming a part of this specification, like characters of reference designating similar parts throughout the several views, wherein:

Figure 1 is a plan view of a plate lifter constructed in accordance with the present invention. Fig. 2 is a section on the line 2—2 of Fig. 1. Fig. 3 is a detailed fragmentary side elevation thereof.

Referring specifically to the accompanying drawings, the improved plate lifter is shown as constituted of an integral section of wire bent upon itself to form a bow-shaped connecting portion 1, from which project resilient arms 2, the normal tendency of which is to spring outwardly. The connecting portion 1 merges with the arms 2, and forms substantial depressions 3 at the rear ends of said arm, which augment the resiliency thereof. The arms 2 at their front ends are extended

downwardly as at 4, and then horizontally and curvingly as at 5, to engage the plate. A metallic clip 6 serving as a handle, has its edge bent as at 7 about the portion 1. The clip 6 likewise serves to prevent spreading of the sides of this bowed portion. An adjusting slide 8 in the form of metallic clip or sleeve is engaged about the arms 2. Movement of the slide 8 forwardly will draw said arms together, and movement of the same rearwardly will permit them to spread apart. It will be understood that the arms 2 spring apart from the depressions 3.

The plate lifter comprehended in the present invention is simple in its structural details, inexpensive to manufacture and practical and efficient in use.

From the foregoing description it will be seen that simple and efficient means are provided for accomplishing the objects of the invention.

What is claimed is:

A plate lifter comprising a section of wire bent upon itself to afford a bow-shaped connecting portion and including parallel forwardly projecting arms, said connecting portion merging with said arms and forming depressions, said arms being extended downwardly at their frontends, and then outwardly and curvingly, a clip having its sides bent upon the sides of said connecting portion to confine the same against spreading and a clip or sleeve surrounding said arms for slideable movement as and for the purpose set forth.

In testimony whereof, I affix my signature, in presence of two witnesses.

OSCAR E. PLEMON.
